CRIMPING TOOL

James B. Dennis, West Lanham Hills, Md.

Application September 17, 1942, Serial No. 458,664

4 Claims. (Cl. 86—39)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to apparatus for crimping cartridge cases to secure projectiles therein. It is adapted particularly for any large sized fixed ammunition where the crimping is secured by forming circumferential or peripheral dents in the cartridge case metal a short distance below the end of the case, the inner surface of these dents engaging in a groove formed in the exterior of the projectile.

An object of the invention is to provide a crimping tool assembly which is very simple in character and in its mode of operation, and which will permit the insertion of a loaded cartridge into the machine so that one end of the cartridge is wholly free. A further object is to provide a crimping tool assembly which will produce no axial reactions on the cartridge so that in its operation, an operator may insert a cartridge into the machine, effect the crimp, and withdraw the cartridge with no need for clamping the cartridge in position while the crimping operation is effected. A further object of the invention is to produce a crimping groove in the cartridge which will be substantially coextensive with the periphery of the case, thus anchoring the projectile more firmly in the case than has been accomplished by previous methods. The previous system included the formation of a plurality of short segmental dents in the cartridge case which, though giving fair security, were not as effective in retaining the projectile in the case as the present system.

A better understanding of the details of the invention will be gained in reading the annexed detailed description in connection with the drawing, in which:

Figure 1 is a longitudinal section through the elements of the mechanism, and

Figure 2 is a section on the line 2—2 of Figure 1.

In Figure 1, 10 represents a support or table having a threaded opening in which is screwed an abutment 11 having a flat top 12 and having a threaded recess 13 into which is screwed a bushing 14 having a tapered bore 15. The bore 15 is complementary to the tapered part of a cartridge case 16, so that, when the case is passed through the bushing 14 from below, the bushing provides a positive stop to locate the case for a certain axial position with respect to the top face 12 of the abutment 11. Above the abut-

ment is a reciprocable sleeve 17, hollow as at 18 to provide clearance for the projectile 19 of the cartridge when the latter is in the position shown. The top of the sleeve 17 is carried by a press ram, a portion of which is shown at 20. The bottom end of the sleeve 17 is interiorly chamfered as at 21, and fitted to this chamfered surface are a plurality of segments 22 each having a tapered portion 23 engaging the sleeve chamfer 21 and having projecting beads 24 which, when the segments 22 are moved radially inwardly against the cartridge case 16 form a crimping groove therein. The segments 22 are loosely secured to the sleeve 17 by studs 26 passing through slots 27 in the sleeve, the studs being screwed into the segments and having springs 28 and nuts 29 so that the segments may not drop away from the sleeve.

In operation, the sleeve 17 is raised slightly from the abutment 11 allowing the segments 22 to move radially outwardly. A cartridge is inserted through the bore 15 as far as it will go, whereupon the sleeve 17 is lowered forcing the elements 22 inwardly to crimp the cartridge case by virtue of the camming action of the sleeve upon the conical portions 23 of the segments. The bottom surfaces of the segments bear against the face 12 of the abutment 11 which prevents the segments from moving axially along the cartridge case or from causing any axial force reaction upon the cartridge case. Upon raising of the sleeve 17, the segments 22 are freed from the cartridge case and the latter may be withdrawn from the tool assembly.

The use of a plurality of crimping segments 22 allows of the formation of a circumferential groove in the cartridge case; however, if a plurality of short segmental grooves are desired, the projections 24 may be formed accordingly.

With proper proportioning, the crimping assembly may be adapted for several different types or calibers of projectiles. The only elements which need be changed to adapt the apparatus for different projectiles would be the bushing 14 and the crimping segments 22.

It is obvious that this apparatus may readily be adapted for use as a production tool or alternately it may be used for a hand-loading setup. The shape of the crimping projections 24 should be so chosen as to minimize the possibilities of cracking in the cartridge cases which, as it is well known, are usually made of brass.

While I have described my invention in detail in its present preferred embodiment, it will be obvious to those skilled in the art, after under-

standing my invention, that various changes and modifications may be made therein without departing from the spirit or scope thereof. I aim in the appended claims to cover all such modifications and changes.

What I claim is:

1. In a crimping assembly for a cylindrical member, a stationary base for the said assembly having an aperture for guiding and locating the member and having a plane surface normal to the member axis, a plurality of projection-carrying segments arranged around the member resting on said plane surface and slidable thereon, said segments having conical outer portions and the projections thereof being adapted to engage and deform said member, and a reciprocable sleeve adapted to be pressed downwardly relatively to the said stationary base into engagement with conical portions of said segments to move them inwardly for crimping said member.

2. In a crimping assembly for securing projectiles in tapered cartridge cases, a support having an opening through which the projectile and a portion of the case is passed, a bushing secured to the support within said opening having a taper complementary to the case taper to provide axial location for the case and to gauge the portion of the case above the said support, a plurality of radially movable crimping elements for denting the case below the upper edge thereof into projectile engagement, and means to move said elements.

3. A crimping assembly comprising a hollow ram having an internally chamfered open end, a plurality of segmental elements having conical

faces engaged with the said ram chamfer, whereby relative axial movement of the said elements and the ram effects inward movement of the elements into engagement with the cartridge case, the said ram being provided near its said

open end with a plurality of slots equal to the said plurality of segmental elements, the segmental elements being provided with stud bolts passing through the respective ones of the said ram slots, and springs at the distal ends of the said bolts compressed upon the said axial movement of the ram and adapted upon the return movement of the ram to effect outward movement of the elements away from the cartridge case.

4. In a machine for securing a projectile in a cartridge case, a stationary horizontal base having an aperture therethrough for guiding and locating the projectile and having a plane surface normal to the axis of said case, a plurality of segments each having a flat undersurface in sliding contact with said plane surface whereby true horizontal movement of the segments is assured, said segments being provided adjacent their lower inner peripheries with case indenting means, and with outer conical portions, a reciprocable hollow sleeve above the segments for the reception of the projectile, said sleeve being provided with means coacting with said conical portions of the segments upon the downward movement of the sleeve to simultaneously move said segments inwardly to dent the case into locking engagement with the projectile.
